UNITED STATES PATENT OFFICE.

WILLIAM J. ORR, OF BANGOR, MAINE.

LOCOMOTIVE COAL-SPRAYER.

1,033,924.

Specification of Letters Patent. Patented July 30, 1912.

Application filed March 23, 1912. Serial No. 685,877.

To all whom it may concern:

Be it known that I, WILLIAM J. ORR, a citizen of the United States, residing at Bangor, in the county of Penobscot and State of Maine, have invented certain new and useful Improvements in Locomotive Coal-Sprayers, of which the following is a specification, reference being had to the accompanying drawings.

10 This invention comprehends certain new and useful improvements in sprayers and relates more particularly to sprayers for use in dampening coal on locomotive tenders.

The primary object of the invention is to provide a sprayer of this nature which shall be simple in construction and especially adapted to the work in question.

At the present time it is customary for the fireman on a locomotive to spray water over the coal on the tender to prevent the coal blowing away and being wasted and also to prevent it blowing into the eyes of the engineer and fireman. This necessary operation is now done by using a hose similar to a garden hose, which takes much of the fireman's valuable time. My invention is designed to relieve the fireman of this unnecessary labor.

With these objects in view as well as others which shall become apparent as the description proceeds the invention consists in certain constructions and arrangement of parts as shall be hereinafter fully described, claimed and illustrated in the accompanying drawing, in which—

Figure 1 is a top plan view of my device positioned on a tender; and Fig. 2 is a side elevation of the same.

Similar parts are referred to in the description and designated in the accompanying drawing by like reference characters.

Referring to the drawing by numerals, 1, designates a section of rubber hose just long enough to take up the motion between the tender and locomotive. This piece of hose conducts the hot water and steam, as it comes from the locomotive injector, to my device.

The sprayer consists of a supply pipe 2, one end of which is connected by the coupling 3 to the hose 1, and the other end of which is connected by the T-coupling 4 to the spraying pipe 5. This pipe is closed at its ends by the screw caps 6 and is provided on one side with a series of alined orifices 7 arranged longitudinally thereof.

The sprayer is secured transversely of the forward end of the tender on a supporting member A by the cap-plates 8, which being positioned adjacent the end caps 6 and over the spraying-pipe 5, allow said pipe to turn about its longitudinal axis and restrain it from moving in any other direction. One of the cap-plates 8 is provided with a clamping-screw 9 which may be tightened upon the pipe 5 holding it in any desired position. Base-plates 10, placed under the cap-plates 8 and spraying-pipe 5 space said pipe from the tender so that it may turn freely. The supporting member A is notched at 11 to provide a space for the supply-pipe 2 to rest in when the sprayer is not being used.

It will be seen from the foregoing description in connection with the accompanying drawing, that I have provided a simple form of sprayer adapted for use on a locomotive tender; one which may be adjusted to spray any portion of the coal on said tender.

What I claim is:—

1. In a device of the class described, the combination with a body member, of a spraying-pipe positioned longitudinally thereof, base plates secured to said body member and spacing the spraying-pipe therefrom, cap plates positioned over the spraying-pipe and secured to the base plates, caps closing the ends of the spraying-pipe and coöperating with the cap and base plates to prevent longitudinal movement of the spraying pipe and a clamping screw threaded through one of the cap plates and adapted to engage the spraying-pipe to hold the same in rotational adjustment.

2. In a device of the class described, the combination with a body member, of a spraying-pipe positioned longitudinally

thereon, base plates secured to said body members and spacing the spraying - pipe therefrom, cap plates positioned over the spraying-pipe and secured to the base plates, 5 means for closing the ends of the spraying-pipe and coöperating with the cap and base plates to prevent longitudinal movement of the spraying pipe, and means carried by the

cap plates to engage the spraying-pipe to hold the same in rotational adjustment. 10

In testimony whereof I hereunto affix my signature in the presence of two witnesses.

WILLIAM J. ORR.

Witnesses:

JAMES F. SINGLETON,
EDWARD P. MURRAY.
